UNITED STATES PATENT OFFICE

138,229

DESIGN FOR A TOY ANIMAL BLOCK

Eoina Nudelman, Chicago, Ill.

Application April 24, 1944, Serial No. 113,351

Term of patent 7 years

(Cl. D34—2)

To all whom it may concern:

Be it known that I, Eoina Nudelman, a citizen of France, residing at Chicago, in the county of Cook and State of Illinois, have invented a new, original, and ornamental Design for Toy Animal Blocks, of which the following is a specification, reference being had to the accompanying drawing, forming part thereof,

Fig. 1 is a front elevational view of a toy animal block, showing my new design;

Fig. 2 is a left-hand side view; and

Fig. 3 is a right-hand side view.

I claim:

The ornamental design for a toy animal block, as shown.

EOINA NUDELMAN,
